ATTORNEYS

UNITED STATES PATENT OFFICE.

WILLIAM E. CRUMP, JR., OF SEALY, TEXAS.

CORK-EXTRACTOR.

SPECIFICATION forming part of Letters Patent No. 350,350, dated October 5, 1886.

Application filed July 22, 1886. Serial No. 208,757. (No model.)

To all whom it may concern:

Be it known that I, WILLIAM E. CRUMP, Jr., a citizen of the United States, residing at Sealy, in the county of Austin and State of Texas, have 5 invented certain new and useful Improvements in Cork-Extractors; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation 15 of this invention, and is a perspective view. Fig. 2 is a vertical section. Fig. 3 is also a perspective view. Fig. 4 is a bottom view of the cork.

This invention relates to cork-extractors; 20 and it consists in the construction and novel arrangement of devices, all as hereinafter described, and pointed out in the claim.

In the accompanying drawings the letter A designates the bottle-neck having the exterior shoulder B. C is the cork, and D is the wire extractor.

The cork C is usually prepared by cutting slits *e* in opposite sides to receive the branches of the wire, which is doubled, its looped ends 25 *g g* passing upward in the slits of the cork on

opposite sides. The loop ends are designed to be long enough to fold across the top of the cork and down to the shoulder of the neck of the bottle, where they are fastened in place by the securing-wire *h*, which passes around the 35 neck under the shoulder. When so fastened, the cork is secured in place.

In order to extract the cork, the securing-wire is unfastened or broken and the loop ends of the main wire raised above the cork, 40 and then a knife, key, or other instrument having been passed through the loops the cork can be readily pulled out of its seat.

Having described this invention, what I claim, and desire to secure by Letters Patent 45 is—

The combination, with the side-slitted cork, of the doubled-wire extractor having loop ends engaging the slits of the cork and extending beyond the same and the securing-wire passing through said loop ends and around the shoulder of the bottle-neck, substantially as specified.

In testimony whereof I affix my signature in presence of two witnesses.

WILLIAM E. CRUMP, JR.
